J. C. L. Wright

UNITED STATES PATENT OFFICE.

JOHN DRAPEAU, OF RIVER ROUGE, MICHIGAN.

SALIVA-ARRESTING MEANS FOR TOBACCO PIPES.

Application filed October 6, 1924. Serial No. 742,023.

To all whom it may concern:

Be it known that I, JOHN DRAPEAU, a citizen of the United States, residing at River Rouge, in the county of Wayne and State of Michigan, have invented new and useful Improvements in Saliva-Arresting Means for Tobacco Pipes, of which the following is a specification.

The object of my present invention is the provision of simple, inexpensive and efficient means for use in tobacco pipes with a view to preventing the passage of saliva from and to the mouth of the smoker, i. e., from mouth to stem portion adjacent to the bowl and vice versa.

To the attainment of the foregoing, the invention consists in the improvement as hereinafter described and definitely claimed.

In the accompanying drawings, forming part of this specification:—

Figure 1 is a general sectional view of a tobacco pipe including the preferred embodiment of my invention.

Figure 2 is an enlarged detail section showing the rear section of the pipe stem.

Figure 3 is an enlarged section of the mouth piece.

Figure 4 is an enlarged section of my novel saliva arrester.

Similar numerals of reference designate corresponding parts in all of the views of the drawings.

The stem of the tobacco pipe shown is made in sections, and the rear section 1 is constructed in accordance with my invention. It is to be understood, however, that the stem may be formed in one piece without affecting my invention, and therefore the section 1 will be hereinafter referred to as

the pipe stem. Said stem is provided with the usual bore 2 for the passage of smoke, and the said bore 2 is merged at its rear end into an enlarged bore 3, which, in turn, is merged into a countersink 4, Figures 1 and

3. The said countersink 4 is designed to receive in flush manner the circumferential rib 5 on the body 6 of my improvement, which body is removably arranged in the stem 1. In the body 6 is a bore 7 for the passage of

smoke and an enlarged rear bore 8. It is within the purview of my invention to form the body 6 of any appropriate material, though I prefer to make the said body of aluminum. Removably arranged in the en-

larged bore 8 of the body 6 is a trap member 9 which has an abutment 10 to bear

against the end of the body 6 and also has a beveled end 11. In the trap member 9 is a bore 12 which terminates at its rear end in an angularly disposed portion 13 which extends to one side of the member 9 as illustrated. Both the rear portion of the body 6 and the trap member 9 are arranged in a mouth piece 14, shaped interiorly and exteriorly as illustrated and having a large bore 15 and a minute off-center passage 16 extending rearwardly from the bore 15.

In use the elements are relatively arranged as shown in Figure 1, and hence it will be noted that the improvement will prevent saliva from flowing freely down the stem and at the same time will minimize any burning of the tongue due to hot smoke, the smoke being drawn indirectly through the improvement including the arrester and the mouth piece 14.

The improvement has been reduced to actual practice, and such practice has demonstrated that notwithstanding the capacity of the arrester to prevent the passage of saliva to the mouth no excessive moisture has collected in the course of a week of almost constant use in the stem and in the bottom of the pipe bowl.

In curved stems the bevel 11 of the arrester may be and preferably is made greater than in a straight stem such as illustrated.

It will be manifest from the foregoing that when necessity demands the body 6 and the trap member 9 may be removed from the pipe stem and from the mouth piece 14, and the member 9 can be removed from the body 6 to facilitate thorough cleaning of the arrester.

Like the body 6, the trap member 9 is preferably, though not necessarily, formed of aluminum.

I have specifically described the preferred embodiment of my invention in order to impart an exact understanding of the said embodiment. I do not desire, however, to be understood as confining myself to the construction illustrated, my invention being defined by my appended claim within the scope of which changes may be made without departure from my invention.

Having described my invention, what I claim and desire to secure by Letters-Patent, is:—

In a smoking device, the combination of a stem having a smoke passage and also having an enlarged bore at its rear end in com-

munication with a countersink in said end, a mouth piece having a bore and also having an off-center small passage extending rearwardly from said bore to the rear end of the mouth piece, a body arranged in the stem and the mouth piece and having a bore and an enlargement at the rear end thereof and also having a circumferential rib seated in said countersink and a trap member ar-

ranged in the enlarged bore of the body and 10 partially extending rearwardly from the body and disposed in the mouth piece and having a bore with an angularly disposed rear portion and also having a rear beveled end. 15

In testimony whereof I affix my signature.

JOHN DRAPEAU.
